UNITED STATES PATENT OFFICE.

HERBERT P. ORR, OF INDIANA, PENNSYLVANIA, ASSIGNOR OF ONE-FOURTH TO HENDERSON E. DOUGLAS, OF PITTSBURGH, PENNSYLVANIA, AND ONE-FOURTH TO ANDREW CHRISTIANSON, OF BUTLER, PENNSYLVANIA.

METHOD OF FORMING DRAWBAR YOKES.

Application filed February 24, 1922. Serial No. 539,018.

To all whom it may concern:

Be it known that I, HERBERT P. ORR, a subject of the King of Great Britain, and a resident of Indiana, in the county of Indiana and State of Pennsylvania, have invented a new and useful Improvement in Methods of Forming Drawbar Yokes, of which the following is a specification.

This invention relates to a method or process of making draft gear yokes or draw bar yokes, and the object of the invention is to provide an inexpensive and expeditious method of manufacturing yokes of a single piece without seams or joints. It is also an object to make such yokes by a forging process to obviate the difficulties of casting and to secure a product free from the disadvantages incident to those which are formed by casting. It is a further object to form the completed yoke by die forging in which the minimum number of steps or separate operations is necessary.

According to the present invention a billet is pierced, upset and extruded in one set of dies so as to form the head of the yoke, and this partially formed yoke is then subjected to a further extruding operation in another set of dies to elongate the strap portions and complete the yoke.

The invention will be more readily understood from the following description taken in connection with the appended claims.

The method can be described most readily by reference to the die sets used in performing the same, and will, therefore, be set forth in connection with a description of the two separate and independent die sets employed for carrying out the steps of the process.

In the accompanying drawings Fig. 1 is a transverse sectional view taken on the line I—I of Fig. 2; Fig. 2 a vertical transverse sectional view through the die mechanism employed for carrying out the first step of the process, showing the billet in the die and the plunger in its raised position; Fig. 3 a fragmentary vertical sectional view taken in a plane at right angles to that of Fig. 2; Fig. 4 a fragmentary vertical transverse sectional view showing the transformation of the billet and the relative position of the parts at the completion of the first step of the forging operation; Fig. 5 a view similar to Fig. 4 taken in a plane at right angles to said figure; Fig. 6 an elevational view of the partially

formed yoke as it appears at the end of the first forging process; Fig. 7 a view similar to Fig. 6 taken in a plane at right angles thereto; Fig. 8 a vertical transverse sectional view with parts in elevation of the die mechanism employed for carrying out the second step of the forging operation, showing the partially formed yoke within the die and the position of the parts before the descent of the extrusion plunger; Fig. 9 a fragmentary view of the parts illustrated in Fig. 8 showing the relative position of the parts after the plunger has reached its lowermost position to complete the formation of the yoke; Fig. 10 a transverse sectional view taken on the line X—X of Fig. 8; Fig. 11 a view similar to Fig. 9 taken in a plane at right angles thereto; Fig. 12 an elevational view showing the finished yoke after the completion of the forging operations, and Fig. 13 a similar view taken in a plane at right angles to that of Fig. 12.

Two separate sets of dies are used in carrying out the method or process, the first set being illustrated in Figs. 1 to 5 and the second set in Figs. 8 to 11. In order to clarify the showing of the several figures, illustration of the several bolts employed for binding the parts together has been omitted from some of the drawings.

The female member of the first set of dies is mounted in a die holder 1 which is preferably circular in cross section having a substantially rectangular recess 2 at its center in which the several sections comprising the composite die member are retained and held in position between locking wedges 3 and 4, respectively, the bottom of the recess being closed by a base plate 5 bolted to the holder 1.

The female die comprises an upper section 6 and lower section 7, each of which is split throughout its entire height to form correspondingly shaped sub-sections, those of the upper section 6 being shown at 8 and 9 in Fig. 1, which are bound against the sides of interlocking wear strips 10 and 11 extending the full height of the die, all of said parts being bound together to form a unit by means of spaced bolts indicated at 12.

The conformation of the surface of the central recess in the upper section corresponds to that of the exterior lateral surface of the jaw portions 13 of the formed yoke, and the recess formed between the cooperat-

ing parts of the lower section 7 is such as to conform in outline but is of somewhat less length than the strap portions of the yoke, the upper extremity of the latter recess being enlarged at opposite sides as indicated at 5 14 and 15 throughout a short extent into which the lower end of the plunger 16 projects during its downward movement for a purpose to be presently described.

10 Plunger 16 is rectangular in cross section, having its body portion of such dimensions as to fill the opening of the die as clearly shown in Figs. 4 and 5. The lower extremity is cut away in the manner illustrated by 15 Figs. 2 and 3 leaving overhanging ledges 17 and 18 having a curvature corresponding to the edges 19 of the jaws 13, and providing a nose of tapered form.

The cavity of the die, as viewed in Fig. 3, 20 is of uniform width throughout its extent and equals that of the corresponding dimension of the body of plunger 16. The cavity, however, as viewed in a plane at right angles thereto, see Fig. 2, conforms to the shape of 25 the jaws 13 throughout the upper section 6, and is of the same width as that of the nose of the plunger throughout the extent of the enlarged portions 14 and 15, below which it is substantially the same width as the strap 30 portions 20 of the finished yoke.

Slidably mounted for reciprocating movement in a duct leading from the bottom of the die cavity through the several parts is an extraction or kick-out plunger 21, the head 22 35 of which lies flush with the floor of the cavity. This plunger extends through the base plate 5, is normally urged towards its lowermost position, and is adapted to be moved upwardly to eject the partially 40 formed yoke after the first step of the forging operation has been completed. Reciprocation thereof may be caused by any well known means such as a hydraulic pressure cylinder not shown.

45 The operation of the step performed in this first die set is as follows: A billet *a* of metal heated to the proper temperature is placed in the die cavity, as shown in Figs. 1 to 3, and pressure applied to plunger 16. 50 As the plunger descends it pierces the billet spreading a part of the metal into contact with the wall of the upper section 6, forcing a portion of it downwardly into the cavity of the lower section 7 and extruding a portion 55 upwardly around the nose of the plunger, bringing it into position to be contacted by the ledges 17-18 as the plunger continues to descend. After the nose of the plunger has completely pierced the billet it 60 enters the enlargements 14-15 of the cavity in the lower section 7, as shown in Fig. 4, effecting a shearing action at the points 23 and 23' and thus separates the jaws 13 from the strap portions 20 of the partially formed 65 yoke, and at the same time shapes the edges

19 by confinement of the metal below the ledges 17 and 18.

Figs. 4 and 5 shows the plunger after it has reached its limit of downward movement and has completed the first step in the 70 forging operation. In such operation, the billet *a* has been shaped into a partially formed draw bar yoke, the jaws 13 of which have been forced to assume their final shape, and which jaws are connected by short strap 75 portions 24 to a thick end portion *b*.

In actual practice, it is found that during the movement of the plunger into the enlargements 14-15, effecting the piercing action above referred to and the initial 80 formation of the strap portions 24 adjacent the jaws of the yoke, a small quantity of metal will be forced ahead of the plunger nose resulting in the formation of a narrow 85 rib or bead *c* at the juncture of the members 24 and the end portions *b*. The partially formed yoke as it appears after treatment in the first set of dies is illustrated in Figs. 6 and 7, and is ejected in this form by reciprocation of the knick-out plunger 21 after 90 the plunger 16 has been raised.

The die set for completing the formation of the yoke will now be described. The female part of this set is also composed of a number of parts comprising the complete 95 structure and is similar to the first set in having a base plate, die holder, locking wedges and an ejection plunger which, therefore, need not be particularly described.

The die proper comprises the members 30, 30', 31, 31' and a U-shaped wear member 32 having the upper limbs 33, 33', all of which are bolted together as a unit similarly to the method employed in the first die set. Mounted for reciprocation in suitably formed guide ways and disposed adjacent the die cavity is a pair of cutter blocks 34, 34' provided with shearing or cutting edges 35, 35' at their upper ends, and are so formed as to center the plunger 36 which is provided with a slightly reduced extremity 37 corresponding in width to the space between the bodies of the cutting blocks 34, 34' into which the metal *b* is to be forced. The blocks 34, 34' are mounted upon rods 38, 38' yieldingly urged to the position shown in Fig. 8 by any suitable means, not shown, so as to permit their moving bodily downwardly after the plunger has moved sufficiently to positively contact the same.

As clearly shown in Figs. 8 to 11, the cross sectional shape of the plunger 36 is rectangular throughout its length, fitting between the cutting edges 35, 35' at the upper ends of the blocks 34, 34' and spaced from each of the limbs 33, 33' of the intermediate wear member 32 a distance equal to the thickness of the strap portions 20.

The operation of the second set of dies and the changes produced thereby are as

follows: The partially formed yoke in the form it leaves the first die set, as illustrated in Figs. 6 and 7, is placed in the position shown in Fig. 8 and the end 37 of the 5 plunger 36 brought into contact with the upper surface of the thickened portion *b*, the body of the plunger filling the opening between the jaws 13 and the short strap portions 24. When pressure is applied to the 10 plunger the partially formed yoke is brought home in the die, shearing or cutting off the ribs *c* by means of the cutting edges 35, 35', the yielding supporting means for the blocks 34, 34' offering sufficient resistance 15 to assure such action. As soon as the enlarged section of the plunger firmly contacts the blocks 34, 34', however, they are forced bodily downwardly, the plunger and blocks moving together as a unit, bringing 20 the bottom surface of the thickened portion *b* into contact with the floor of the die cavity, while continued downward movement of the plunger extrudes the metal of the part *b* around the opposite sides of the 25 plunger through the space provided between the plunger and the limbs 33, 33', causing the elongation of the strap portions of the yoke. This extruding action is continued until the end portion 39 connecting the 30 straps 20 is reduced to about the same thickness as the straps, the several parts assuming the positions shown in Fig. 9. During this extrusion of the metal of the part *b*, jaws 13, previously formed, gradually slide upwardly along the sides of the plunger which 35 functions as an internal guide. The completely formed draw bar yoke is then ejected after withdrawal of the plunger by actuation of the ejection or kick-out device in identically the same manner as previously described in connection with the first die set. 40

The completely formed forging as it leaves the second die set, as illustrated in Figs. 12 and 13, can be subjected to any further finishing steps that are found to be desirable, such as punching operations for forming apertures for pins or other similar devices.

It is thus seen that the yoke is completely 50 forged in but two steps in the first of which the head or jaw portions are formed, and in the second of which the straps and connecting end portions are produced, and that a product is secured containing the customary 55 open spaces between the head, strap and connecting end portions, thus obviating the necessity of additional steps to produce such spaces after the completion of the forging operation.

60 I claim:

1. A method of forming draw bar yokes which comprises forcing a plunger entirely through a billet to form a hollow head with

a substantially even surfaced opening extending completely through the head, and 65 subsequently subjecting the end opposite the head so formed to extrusion to produce side straps thereon.

2. A method of making draw bar yokes which comprises the subjection of a billet 70 to pressure between a plunger and die, forcing the plunger entirely through the billet to form a hollow head, with a thickened end portion and straps therebetween whereby all fins formed by the metal in advance 75 of the plunger will project laterally outwards and be disposed upon the exterior surface of the said thickened end portion, and subsequently subjecting the partially formed yoke to pressure between a second 80 plunger and second die extruding the metal of the thickened end portion to elongate said straps and shearing off said external fins.

3. A method of forging draw bar yokes which consists in subjecting a solid blank 85 to pressure between a plunger and die to force the plunger completely through the blank to form a hollow head having a substantially smooth opening extending completely through the head and outwardly flared jaws at one extremity and a thickened portion spaced therefrom at the other, and subsequently extruding the metal of the said thickened portion to form 90 elongated side straps thereon.

4. A method of making draw bar yokes which consists in subjecting a solid billet 100 to pressure between a plunger and die to force the plunger completely through the billet and extrude the metal thereof to form a hollow head at one end having a substantially even-surfaced opening extending entirely through the head and a thickened portion at the other and straps therebetween, and then extruding the metal of the thickened portion to elongate said straps.

5. A method of making draw bar yokes which comprises the subjection of a billet to 110 pressure between a plunger and die to force the plunger entirely through the billet, simultaneously piercing, upsetting and extruding the metal thereof to form a hollow head having a substantially smooth opening extending completely through the head 115 with side straps and a thickened portion connecting the extremities of the side straps, and subsequently extruding the metal of the thickened portion to elongate said straps.

120 In testimony whereof, I sign my name.

HERBERT P. ORR.
